UNITED STATES PATENT OFFICE.

AUGUST C. DITTRICH, OF CHICAGO, ILLINOIS.

DESIGN FOR AN EMBLEM OR SIMILAR ARTICLE.

Application filed April 8, 1925. Serial No. 13,058. Term of patent 7 years.

To all whom it may concern:

Be it known that I, AUGUST C. DITTRICH, a citizen of the United States, residing at Chicago, Illinois, have invented a new, original, and ornamental Design for Emblems or Similar Articles, of which the following is a specification, reference being made to the drawing forming a part thereof.

In the annexed drawing the Fig. 1 is an edge view and Fig. 2 is a face view of the emblem or similar article.

I claim:

The ornamental design for an emblem or similar article substantially as shown.

AUGUST C. DITTRICH.
